Primary Examiner — Ruth McInroy

(57) **CLAIM**

I claim the ornamental design for a vacuum hose attachment, as shown and described.

DESCRIPTION

FIG. 1 is a top, front and left side perspective view of a vacuum hose attachment showing my new design;

FIG. 2, a bottom, rear and right side perspective view thereof;

FIG. 3, a top plan view thereof;

FIG. 4, a rear elevation view thereof;

FIG. 5, a bottom plan view thereof;

FIG. 6, a front elevation view thereof;

FIG. 7, a left side elevation view thereof;

FIG. 8, a right side elevation view thereof; and,

FIG. 9, a cross-sectional view taken along line 9-9 in FIG. 6.

1 Claim, 5 Drawing SheetsFIG. 1

FIG. 2

FIG. 3

FIG. 4

FIG. 7
